CARBON PAPER PAD

Robert J. Fuerst and Fritz Michel, New York, N. Y.

Application July 11, 1951, Serial No. 236,122

5 Claims. (Cl. 282—22)

The present invention relates to a pad of carbon paper sheets and more particularly to a pad the carbon paper sheets of which have equal sizes corresponding substantially to the size of a normalized letter sheet.

It is an object of the present invention to provide a pad of carbon paper sheets from which the carbon paper sheets can be easily removed.

It is another object of the present invention to provide a pad of carbon paper sheets in which each sheet after the removal thereof is provided with marks indicating the first and last line to be written or printed on the letter sheet to be used in connection with the carbon paper sheet.

It is a further object of the present invention to provide a pad in which the carbon paper sheets can be easily marked with arbitrary marks by the operator.

A pad of carbon paper sheets according to the present invention comprises in its broadest aspects a plurality of carbon paper sheets, the carbon paper sheets having equal sizes and being each provided with an edge portion being free of carbon, a folder having substantially the same size as the carbon paper sheets, and means for fastening the carbon paper sheets at the carbon free edge portion thereof to the folder adjacent to the folded edge thereof, the fastening means allowing to tear out said carbon paper sheets from the folder and being arranged so as to mark the carbon free edge portions of the carbon paper sheets with marks having a predetermined location on the carbon paper sheets.

In a preferred embodiment of the present invention a division is arranged on the outside of the folder along the folded edge thereof in alignment with, and above, the carbon free edge portions of the carbon paper sheets, and means such as a layer of wax are arranged on the inside of the folder underneath the division for marking the carbon free edge portion of the uppermost one of the carbon paper sheets with additional marks according to indentations made on the division by the operator.

Preferably the folder has a base portion and a cover portion connected to the base portion along one edge of the folder being the folding edge adjoining to which the carbon free edge portions of the carbon paper sheets are fastened to the base portion.

In a preferred embodiment of the present invention the fastening means include two parts separated from each other by a predetermined distance.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a perspective view of the pad according to the invention with the folder thereof in folded position;

Fig. 2 is a perspective view of the pad shown in Fig. 1 with the folder thereof in open position; and

Fig. 3 is a perspective view of a single carbon paper sheet after removal thereof from the pad.

Referring now to the drawings and first to Figs. 1 and 2, the pad comprises a folder generally denoted by 10 and including a base portion 12 and a cover portion 14 which are connected to each other along one edge portion 16 about which the folder 10 in the position shown in Fig. 1 is folded.

2

A plurality of carbon paper sheets 18, a single one of which is shown in Fig. 3, is fastened to the base portion 12 of the folder 10, for instance stapled by means of staples 20 and 22 forming two parts which are separated from each other by a predetermined distance. The carbon paper sheets 18 are provided with carbon free edge portions 24, respectively, with which the carbon paper sheets 18 are stapled together as clearly shown in Fig. 2. Preferably the parts 26 and 28 of each carbon free edge portion 24 which are arranged in the vicinity of the staples 20 and 22, respectively, are separated from the bulk of the edge portion 24 by perforations 30 and 32 which allow an easy removal of the carbon paper sheets from the pad, the edge portion 24 having after removal of the carbon paper sheet 18 two recesses 34 and 36. It should be noted that the recesses 34 and 36 have a predetermined distance from each other corresponding substantially to the predetermined distance between the staples 20 and 22 and thus can be used for marking the first and last lines of the latter sheets (not shown) to be used in connection with the carbon paper sheets and covering only the bulk portion thereof but not the carbon free edge portions. These lines correspond to the outer points 38 and 40 of the recesses 34 and 36, respectively. The carbon paper sheets 18 are preferably provided with a cut-away corner 42, for instance in the shape of a quarter of a circle, over which the letter sheets (not shown) protrude so that the carbon paper sheets can be easily removed from the letter sheets (not shown), by grasping the carbon paper sheets with one hand at the carbon free edge portions 24 thereof which project beyond the letter sheets, and the letter sheets at the portions protruding over the cut-away corners 42. Preferably the carbon paper sheets are made of curl-proof carbon paper which lies flat under normal conditions. Instead of stapling the carbon paper sheets 18 to the base portion 12 of the folder 10 other fastening means can be used, for instance a gluing applied to parts 26 and 28 of the carbon free edge portion 24.

The cover portion 14 of the folder 10 is provided with a cut-out 44 preferably arranged at the center of the edge opposite to the folding edge 16 in order to facilitate the removal of carbon paper sheets without opening the folder 10.

Adjacent to the folding edge 16 the cover portion 14 is provided with a scale 46 on the outside of the folder and means such as a layer of wax 48 are arranged on the inside of the folder underneath the scale 46 for marking the carbon free edge portion 24 of the uppermost one of the carbon paper sheets 18.

The operation of this device is as follows:

The pad is taken into use in the position shown in Fig. 1, with the cover portion or sheet 14 folded above the carbon paper sheets 18 which are stapled to the base portion 12 of the folder. Carbon sheets 18 can now be removed from the pad by gripping them at the portion 50 thereof which is left free by the cut-out 44 of the cover portion 14. By pulling out a carbon paper sheet 18 from the pad the carbon free edge portion 24 thereof is recessed at 34 and 36 so that the outer points 38 and 40 can be used for an indication of the first and last lines of the letter sheets (not shown) to be used in connection with the carbon paper sheets the sizes of which are normalized and substantially equal. It should be understood, however, that the carbon free edge portion 24 of the carbon paper sheet 18 projects beyond the edge of the letter sheets.

If it is intended to mark special lines on the carbon paper sheet 18 which correspond to certain lines on the letter sheet (not shown), the operator marks the appropriate subdivision of the scale 46 with his fingernail, a

pencil or the like. In consequence thereof corresponding marks such as 52 are transferred to the carbon free edge portion 24 of the uppermost carbon paper sheet 18 before the removal thereof. In this way a very simple but reliable marking of the carbon paper sheet 18 is achieved.

It will be understood that each of the elements described above, or two or more together, may also find a useful application in other types of pads of carbon paper sheets differing from the types described above.

While the invention has been illustrated and described as embodied in a pad the carbon paper sheets have equal sizes, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by 25 Letters Patent is:

1. A pad of carbon paper sheets, comprising in combination, a plurality of carbon paper sheets, said carbon paper sheets having equal sizes and being each provided with an edge portion being free of carbon; perforations separating, respectively, a part of said carbon free edge portion of each of said carbon sheets from the bulk of said edge portion; a folder having substantially the same size as said carbon paper sheets, said folder having a base portion and a cover portion connected to said base portion along one edge of said folder; means for fastening said parts of said carbon free edge portions of said carbon paper sheets to said base portion adjoining said edge of said folder connected to said cover portion, whereby when said carbon paper sheets are torn out from said folder said perforations form recesses in the carbon free edge portions of said carbon paper sheets having a predetermined location on said carbon paper sheets; scale means arranged on the outside of said folder along the edge thereof and in alignment with, and above, the carbon free edge portions of said carbon paper sheets; and means arranged on the inside of said folder underneath said scale means for marking the carbon free edge portion of the uppermost one of said carbon paper sheets with additional marks according to indentations made on said scale means by the operator.

2. A pad of carbon paper sheets, comprising in combination, a plurality of carbon paper sheets, said carbon paper sheets having equal sizes and being each provided with an edge portion being free of carbon; perforations separating, respectively, a part of said carbon free edge portion of each of said carbon sheets from the bulk of said edge portion; a folder having substantially the same size as said carbon paper sheets, said folder having a base portion and a cover portion connected to said base portion along one edge of said folder; means for fastening said parts of said carbon free edge portions of said carbon paper sheets to said base portion adjoining said edge of said folder connected to said cover portion, whereby when said carbon paper sheets are torn out from said folder said perforations form recesses in the carbon free edge portions of said carbon paper sheets having a predetermined location on said carbon paper sheets; scale means arranged on the outside of said folder along the edge thereof and in alignment with, and above, the carbon free edge portions of said carbon paper sheets; and a layer of wax arranged on the inside of said folder underneath said scale means for marking the carbon free edge portion of the uppermost one of said carbon paper sheets.

with additional marks according to indentations made on said scale means by the operator.

3. A pad of carbon paper sheets, comprising in combination, a plurality of carbon paper sheets, said carbon paper sheets having equal sizes substantially corresponding to the size of a normalized letter sheet and being each provided with an edge portion being free of carbon, said carbon free edge portions of said carbon paper sheets being arranged along the longer edge thereof; a folder having substantially the same size as said carbon paper sheets, said folder having a base portion and a cover portion connected to said base portion along one edge of said folder; means for fastening parts of said carbon free edge portions of said carbon paper sheets to said base portion adjoin 10 ing said edge of said folder connected to said cover portion, said fastening means including two parts separated from each other by a predetermined distance; perforations separating, respectively, said parts of said carbon free edge portions of each of said carbon sheets from 15 the bulk of said edge portions, said perforations defining, respectively, recesses in said edge portions having outer points having a predetermined location on said carbon paper sheets whereby when said carbon paper sheets are torn out from said folder, said outer points mark the carbon free edge portions of said carbon paper sheets with 20 marks having a predetermined location on said carbon paper sheets; scale means arranged on the outside of said folder along the edge thereof and in alignment with, and above, the carbon free edge portions of said carbon paper 25 sheets; and a layer of wax arranged on the inside of said folder underneath said scale means for marking the carbon free edge portion of the uppermost one of said carbon paper sheets with additional marks according to indentations made on said scale means by the operator.

35 4. A carbon sheet holder comprising, in combination,
a folder adapted to have a stack of carbon sheets located
therein with a carbon-free edge portion of the carbon
sheets located beneath a predetermined part of said folder,
the latter being made of a flexible material and said pre-
40 determined part of said folder having an inner face di-
rected toward the interior of the folder to be aligned with
the carbon-free edge portions of the carbon sheets and
having an outer face directed toward the exterior of the
folder; a scale located on said outer face of said part of
45 said folder; and a layer of wax located against said inner
face of said part of said folder, whereby an impression
made on said scale will be transferred through said part
of said folder and said layer of wax to the carbon-free
edge of the topmost of a stack of carbon sheets located
in said folder.

50 in said folder.

5. An article of manufacture comprising, in combination, a folder having an elongated flexible portion, said flexible portion having an inner face directed toward the interior of the folder and an outer face directed toward the exterior of the folder; a scale located on said outer face of said flexible portion; a layer of wax located against said inner face of said flexible portion; and a stack of carbon sheets located in the interior of said folder, said sheets each having an elongated carbon-free portion in registration with said elongated flexible portion of said folder, whereby an impression made on said scale will be transferred through said flexible portion and said layer of wax to the carbon-free portion of the topmost of said stack of carbon sheets.
